INSULATOR PIN

Application filed July 29, 1922. Serial No. 578,466.

This invention relates to pins for supporting insulators on cross arms or other structures and has for its object the provision of supports of the class named which shall be economical to manufacture and install and in which the material shall be effectively distributed for mechanical strength. Other objects will appear from the following description.

10 The invention is exemplified in the combination and arrangement of parts shown in the accompanying drawing and described in the following specification and it is more particularly pointed out in the appended claims.

15 In the drawings:

Fig. 1 is an elevation of one form of insulator pin embodying the present invention with the supporting flange in section.

20 Fig. 2 is a fragmentary view of a portion of the pin in elevation and with the flange in section showing a slightly different construction from that of Fig. 1.

Fig. 3 is a view similar to Fig. 2 showing another modification.

25 Where insulator pins are mounted on cross arms or other structures it is desired to support the pin without weakening its resistance to bending, especially at the point where the pin joins the supporting structure. If the pin is reduced to provide a supporting shoulder, its resistance to bending will be correspondingly diminished. In the present invention, this difficulty is obviated by providing a flange shown at 10 in the drawing, which 30 projects from a sleeve 11 connected to the pin 12 by threads 13. The threads 13 are preferably rolled threads so that they are formed without removing any of the stock from pin 12.

35 In the rolling process the stock is pressed from the grooves so that the tips of the threads have a greater diameter than that of the original bar. This appears clearly from Fig. 2 of the drawing. Threads 14 may be 40 formed on the lower end of the pin by similar

process and any suitable support 15 for an insulator may be connected at the upper end of the pin. The internal diameter of the threads in the sleeve 11 is equal to that of the original diameter of the bar 12 so that the 50 sleeve 11 will slide freely over the unthreaded portion of the pin, but will mesh with the threads 13. In assembling the parts, the sleeve 11 may be threaded over the portion 14 and it will move freely along the portion be- 55 low the threads 13. When the sleeve is properly positioned on the threads 13 it will support the pin in place on the cross arm.

If it is desired to provide a tighter connection, a portion of the upper edge of the 60 sleeve 11 may be left unthreaded as shown at 16 in Fig. 2. After the flange is in place, the upper edge of the sleeve 11 may be forced inwardly as shown in Fig. 1 to bind tightly 65 against the pin and thus lock the flange against further longitudinal movement. This arrangement also encloses the end of the threads concealing them from view and protecting them from entrance of moisture, es- 70 pecially after the parts have been galvanized. This construction will also provide supplementary support for the pin where it joints the flange and where the bending moment is greatest. If the flange is placed upon the pin from above, the upper edge may be originally 75 formed to fit the pin tightly, or the threads may continue to the top of the flange as shown in Fig. 3 so that the flattened tips of the threads in the flange will bear against the outer surface of the pin.

80 Where the body of the pin 12 is threaded to the base, the depth of the base along the axis of the pin may be relatively short and the pin and base still act as a unit. The upper portion of the pin may be provided with a thread to fit a separable thimble or have a surface suitable for cementing into an insulator. The pin is of small relative diameter and is free from sharp points. This 85 gives a good striking distance between the 90

pin and insulator, thereby developing the maximum insulation in the insulator. As the pin has the same size of body 12 bearing against the sides of the hole as above the base 10 when used with a wooden cross arm, a base of minimum diameter may be used. This is due to the support provided by the sides of the hole in the arm. In most pins the portion through the arm is so small that it is very weak as a beam and must be used as a tension member.

The large diameter of the body 12 is an advantage, as little tension in this member is necessary to develop the maximum ultimate strength of the pin when mounted on a wood arm. As wood cross arms shrink and loosen the tension produced by the nut attached to the threaded end 14, it will be seen that the strength will not be reduced appreciably as in the case of pins which develop a large portion of their ultimate strength due to a large bearing base 10 and tension in the bolt 12. The base 10 may be made of pressed metal, forgings, castings, or any suitable material. It may have a curved base or lips for gripping the cross arm. The base may be provided with teeth for preventing rotation if desired.

I claim:

1. An insulator pin having rolled threads thereon, the points of which project outwardly beyond the periphery of the unthreaded portion of said pin while the roots of said threads extend inwardly beyond the peripheral surface of the unthreaded portion of said pin, and a support having a threaded opening meshing with the tips of the threads of said pin but having a minimum diameter large enough to receive the unthreaded portion of said pin.

2. An insulator pin having threads formed thereon and having an unthreaded portion adjacent said threads, the major diameter of said threads being greater and the minor diameter less than the diameter of the unthreaded portion of said pin, and a support having a threaded opening therethrough meshing with the threads on said pin, the minor diameter of said threaded opening being substantially equal to the diameter of the unthreaded portion of said pin.

3. An insulator pin having threads thereon, the major diameter of which is greater than the diameter of the unthreaded portion of said pin and a support threaded on said pin and having a portion thereof extended inwardly and engaging an unthreaded portion of said pin.

4. An insulator pin having rolled threads thereon, the major diameter of which is greater than the diameter of the pin adjacent said threaded portion, a support through which said pin extends, said support having threads meshing with the threads on said pin and having an unthreaded portion extending

beyond the threads on said pin and projecting inwardly and engaging the unthreaded periphery of said pin adjacent the threaded portion thereof.

5. An insulator pin comprising upper and lower sections of equal diameters, threads on said pin intermediate said sections having a major diameter greater than the unthreaded diameter of said pin and having a minor diameter less than the unthreaded diameter of said pin, a support for said pin having internal threads meshing with the threads on said pin but having a minor diameter substantially equal to the unthreaded diameter of said pin to permit said support to be moved over said unthreaded portion into engagement with the threads on said pin.

6. An insulator pin having an upper and lower section of substantially equal diameters, rolled threads on said pin intermediate said upper and lower section and having a major diameter greater than the diameter of said sections, a supporting flange having a sleeve provided with internal threads arranged to mesh with the threads on said pin and having a minor diameter substantially equal to the diameter of said upper and lower sections, said sleeve having a portion thereof projecting above the threads on said pin and engaging the periphery of the upper section above said threads.

7. An insulator pin having threads thereon the major diameter of which is greater than the diameter of the unthreaded portion of said pin, and a support threaded on said pin and having a portion thereof extending inwardly and engaging the unthreaded portion of said pin at points about the periphery thereof beyond the threaded portion.

8. In combination, a rod having opposite end portions substantially equal in diameter and an intermediate threaded portion, the major diameter of the threads on said threaded portion being greater than the diameter of said rod while the minor diameter of the threads on said threaded portion is less than the diameter of said rod, and a nut having internal threads engaging the threads on said rod, the minor diameter of the threads in said nut being substantially equal to the diameter of said rod while the major diameter of the threads in said nut is substantially equal to the major diameter of the threads on said rod.

9. An insulator pin comprising a pin body, threads on said pin body extending outwardly beyond the periphery of the portion of said body immediately above said threads, a flange for said pin body having a threaded opening meshing with the threads on said pin body and having an inwardly extending portion substantially encircling said pin body and overlying the upper end of the threaded portion of said pin body to enclose the end of said threaded portion, thus concealing the

threads on said portion and protecting them from the weather.

10. An insulator pin having a radially extending portion between the ends thereof and a flange secured to said portion, said flange having the upper extremity thereof formed inwardly over said extending portion substantially throughout the peripheral extent of said portion to enclose said extending portion and lock said flange to said pin.

10 In testimony whereof I have signed my name to this specification on this 25th day of July, A. D. 1922.

ARTHUR O. AUSTIN.
